UNITED STATES PATENT OFFICE.

FRANK H. VAN HOUTEN, OF FISHKILL-ON-THE-HUDSON, NEW YORK, ASSIGNOR
TO DUTCHESSE TOOL COMPANY, OF FISHKILL-ON-THE-HUDSON, NEW YORK,
A CORPORATION OF NEW YORK.

ROTARY BAKE-OVEN.

SPECIFICATION forming part of Letters Patent No. 707,187, dated August 19, 1902.

Application filed October 10, 1901. Serial No. 78,238. (No model.)

To all whom it may concern:

Be it known that I, FRANK H. VAN HOUTEN, a citizen of the United States, residing at Fishkill-on-the-Hudson, in the county of Dutchess, State of New York, have invented certain new and useful Improvements in Rotary Bake-Ovens; and I do hereby declare the following to be a full, clear, and exact description of the same, reference being had to the accompanying drawings, forming a part of this specification, and to the letters of reference marked thereon.

This invention relates to improvements in bake-ovens, and particularly, though not exclusively, to that type of oven designed for baking Vienna bread, the objects of the invention being to provide an exceedingly simple easily-operated rotary oven in which the baking, feeding, and removing of the loaves may be carried on continuously, and in which there will be little loss of heat through exterior radiation and a steady uniform temperature within the baking chamber or oven proper, such as is necessary for baking Vienna and like bread.

The invention consists in certain novel details of construction and combinations and arrangements of parts, all as will be now described, and pointed out particularly in the appended claims.

Referring to the accompanying drawings, Figure 1 is a vertical section taken through an oven embodying the present improvements. Fig. 2 is a horizontal section through the bake chamber or oven proper and looking downwardly on the top of the rotary hearth.

Fig. 3 is a horizontal section through the chamber above the bake-chamber.

Like letters of reference in the several figures indicate the same parts.

The letter A indicates the wall of the oven, preferably made of brickwork or masonry and either circular in horizontal section, as indicated in Fig. 2, or with a circular interior conformation forming circular chambers, in one of which—to wit, the bake-chamber—may be mounted a rotary hearth B. The wall A extends upwardly at the center in the form of a circular well A', at the top of which a

relatively large bearing or track A² is mounted, said bearing or track being adapted to receive a hub B', constituting a portion of the hearth structure. In the preferred construction the bearing A² is mounted in an inclined position, the inclination being from the front upwardly toward the back of the oven, and the bearing-surfaces on the track and hub are made in the form of raceways for balls b, which will constitute an antifriction-bearing and at the same time prevent the lateral displacement of the hearth. The circular chamber in which the hearth is mounted and which constitutes the oven proper is closed at the bottom by a circular arch C, constituting the top or upper wall of a circular flue D, which inclines upwardly from the front to the back of the oven, said circular flue at the front opening into the fire-box E, to which fuel may be applied through a door E' of usual construction. At the rear or highest point the circular flue D communicates with an uptake G, which uptake G in turn opens into an upper circular space or chamber H, extending above the hearth B and baking-chamber, and is preferably inclined downwardly toward the front of the oven, the inclination of said flues or chambers D and H being preferably approximately at the same angle as the inclination of the hearth itself. At the front or lowest portion of the upper circular chamber H a communication is made with a stack or off-take I, in which a suitable damper i may be located for controlling the draft through the flue and around the bake-chamber.

In the construction of the oven the ceiling or top of the bake-chamber may be formed by suitable masonry or metal struts with overlying masonry, and the spaces above said chamber, as well as below the flue D, are preferably filled in with sand or other non-conducting material, whereby the heat is prevented from radiating outwardly.

In constructing the hearth the central hub B' is preferably formed with a bearing-flange B² and a central cylindrical portion B³, provided with a series of apertures through which the inner ends of I-beams B⁴ may be

passed. Said beams are held by bolts B⁵, which extend down between the beams and through a flange in the hub, while the upper ends of said bolts pass through plates B⁶, 5 which overlie the inner ends of the beams. As thus constructed the hub is provided with a series of radial arms, and these radial arms are adapted for the support of slabs of soap-stone, which bridge the space between said 10 arms and rest at their edges on the flanges of the beams. Said slabs are indicated by the letter B and constitute the hearth proper of the oven. They may be fastened in position by any suitable or ordinary fastening means, 15 but are preferably simply laid in place and retained against transverse movement by lugs K, attached to or formed on the outer ends of the arms. Any suitable driving mechanism may be employed for rotating the 20 hearth; but in the preferred construction a circular rack L is secured to the under sides of the arms near their outer ends, and the pinion L', meshing with this rack and mounted on a shaft L², extends through the wall of 25 the oven and is provided with any suitable driving mechanism whereby the oven may be rotated. Obviously a power mechanism may be applied or a hand-wheel, such as indicated at L³, if no power mechanism be available or 30 for any purpose is not desired.

The oven-door through which the bread is inserted and removed is located at the front or lowermost side of the bake-chamber, and it may be of the ordinary tip-up variety, as 35 indicated by the letter M, or of any other preferred type, that shown being preferred, however, for reasons which will now appear.

In baking Vienna bread, as is well known, the oven is filled with steam, and one of the 40 objects of the inclined arrangement is to insure the steam being retained in the oven, inasmuch as it will, owing to its heat, tend to rise away from the openings and remain in the upper portion of the oven, and, further- 45 more, with such an arrangement when the baker opens the door to insert or remove bread the liability of a rush of steam into his face taking place is largely avoided. With a tip-up door it is obvious that the opening is 50 formed at the lowest point first, and hence the baker is able to control the escape of steam to a very large extent, as when it begins to escape too freely the height of the opening may be reduced, leaving only sufficient space 55 for the insertion or removal of the bread.

In operation, the bread having been introduced and placed in position on the hearth, the oven may be rotated so as to move the bread away from the opening, presenting a 60 new and clear space for the reception of more bread, and finally when the hearth is full it will usually be found that the loaves first inserted have been baked and may be removed as they reach the opening and fresh loaves 65 inserted in their stead.

By the arrangement of flues below and above the hearth, but with the walls of said

flues entirely out of contact with the hearth, it is found that the radiated heat maintains a uniform temperature both over and under 70 the bread, whereby an even and uniform crusting is effected without danger of burning or charring the bread.

Having thus described my invention, what I claim as new, and desire to secure by Letters 75 Patent, is—

1. In an oven, the combination with the circular bake-chamber having top and bottom walls inclined in one direction, a circular flue beneath the bottom wall, a circular chamber 80 above the top wall, an uptake connecting the highest point in said flue and chamber respectively, a stack leading from the lowest point in the circular chamber and a fire-box located at the lowest point in the circular 85 flue, of a central support around which said circular flue passes and an inclined circular rotary hearth mounted on said support in the bake-chamber, the inclination of said hearth being substantially coincident with the inclination of the top and bottom walls of the 90 bake-chamber and means for rotating said hearth extending out through the walls of the oven; substantially as described.

2. In a bake-oven, the combination with 95 an inclined flat rotary hearth mounted on a central support to rotate in an inclined plane, of an inclined circular flue underlying said hearth, a circular chamber overlying said hearth, an uptake connecting said flue and 100 chamber and a valved exit leading from said chamber to the smoke-stack; substantially as described.

3. A bake-oven embodying the following construction, to wit, a circular exterior wall, 105 a central circular bake-chamber formed by inclined top and bottom walls, said bottom wall constituting an arch for an inclined flue and said top wall constituting the floor of an inclined unobstructed chamber overlying the 110 bake-chamber, a top wall for said overlying chamber, an uptake connecting the highest point in the inclined flue and overlying chamber respectively, a fire-box at the lowest point 115 in the flue, a smoke-exit at the lowest point in the overlying chamber, a flat rotary hearth mounted on inclined bearings in the bake-chamber and an entrance-door to said bake-chamber located at the lower front side thereof; substantially as described. 120

4. In an oven, the combination with the oven-wall having a circular bake-chamber within the same, a circular flue arranged beneath said chamber, a fire-box at one side of said circular flue, an uptake at the opposite 125 side thereof, a circular chamber overlying the circular bake-chamber and with which said uptake communicates and a smoke-stack communicating with said circular chamber at a point opposite the uptake, an inclined 130 circular rotary hearth mounted in the bake-chamber and means for rotating said hearth extending through the wall of the oven; substantially as described.

5. In a bake-oven, a flat rotary hearth formed with a central hub having a bearing-flange and a central cylindrical portion provided with apertures, I-beams passing through said apertures, a flange on the inside of the hub, plates overlying the inner ends of the beams, bolts passing between the beams through the plates and flange on the inside of the hub, and slabs mounted on the beams; substantially as described.
